(57) **CLAIM**

The ornamental design for a color calibrator for monitor, as shown and described.

DESCRIPTION

1. Color calibrator for monitor

1.1 : Perspective

1.2 : Front

1.3 : Back

1.4 : Left

1.5 : Right

1.6 : Top

1.7 : Bottom

1.8: Perspective view shown in use.

1.9 : Perspective view shown in use.

The broken lines in reproductions 1.8 and 1.9, disclosing a monitor, depict environmental subject matter that forms no part of the claimed design.
